United States Patent Office.

CHARLES GAUTIER, OF WASHINGTON, DISTRICT OF COLUMBIA.

Design No. 2,613, dated April 9, 1867.

DESIGN FOR A BOTTLE.

The Schedule referred to in these Letters Patent and making part of the same.

TO ALL WHOM IT MAY CONCERN:

Be it known that I, CHARLES GAUTIER, of Washington city, in the District of Columbia, have invented, originated, and designed a new Design for a Bottle, of which the following is a full, clear, and exact description, reference being had to the annexed drawings, making part of this specification, in which the bottle is represented by a side elevation.

The bottle is formed with a short and thick body, gradually swelling to the part marked A, and thence tapering to form a comparatively narrow neck, B, with a swell at the mouth, as shown. On the side is a raised crescent, C, enclosing the raised letters forming the following inscription: "C. Gautier's Native Wine Bitters." The bottom is indented deeply, as shown by the dotted lines.

What I claim as my invention, and desire to secure by Letters Patent, is—

The design for a bottle, as herein set forth and shown.

In testimony whereof I have signed my name to this specification in the presence of two subscribing witnesses.

C. GAUTIER.

Witnesses:

JOHN S. HOLLINGSHEAD,

JOHN D. BLOOR.
